Filed Mar. 12, 1962, Ser. No. 69,185

Term of patent 14 years

(Cl. D34—15)

FIGURE 1 is a perspective view of a toy vehicle showing our new design;

FIGURE 2 is a rear elevational view of the toy vehicle illustrated in FIGURE 1;

FIGURE 3 is a perspective view of another embodiment of our toy vehicle design;

FIGURE 4 is a rear elevational view of the toy vehicle illustrated in FIGURE 3;

FIGURE 5 is a perspective view of still another embodiment of our toy vehicle design; and

FIGURE 6 is a rear elevational view of the toy vehicle illustrated in FIGURE 5.

The sides not shown in the various embodiments are substantially the same as that shown. The dominant

features of our design reside in the portion shown in full lines and the shading is to indicate color contrast.

We claim:

The ornamental design for a toy vehicle, substantially as shown and described.
